[57] CLAIM

The ornamental design for a rack for utility, telephone and power cables or the like, as shown and described.

DESCRIPTION

FIG. 1 is a top, front perspective view of a rack for utility, telephone and power cables or the like showing my new design, the rear being flat and unornamented; FIG. 2 is a side elevational view taken from the left of FIG. 1;

FIG. 3 is a front elevational view thereof;
FIG. 4 is a bottom plan view thereof.
